US0D1029812S

(12) **United States Design Patent** (10) **Patent No.:** **US D1,029,812 S**
(45) **Date of Patent:** **** Jun. 4, 2024**

(54) **LED DISPLAY CASING**

(71) Applicant: **QSTECH Co., Ltd.**, Xi'an (CN)

(72) Inventor: **Jing Liu**, Xi'an (CN)

(73) Assignee: **QSTECH CO., LTD.**, Xi'an (CN)

(**) Term: **15 Years**

(21) Appl. No.: **29/846,004**

(22) Filed: **Jul. 12, 2022**

(30) **Foreign Application Priority Data**

Jan. 27, 2022 (CN) 202230057138.0

(57) **CLAIM**

The ornamental design for a LED display casing, as shown and described.

DESCRIPTION

FIG. 1 is a right front perspective view of a LED display casing showing the claimed design;

FIG. 2 is a right rear perspective view thereof;

FIG. 3 is a front view thereof;

FIG. 4 is a rear view thereof;

FIG. 5 is a left side view thereof;

FIG. 6 is a right side view thereof;

FIG. 7 is a bottom view thereof; and,

FIG. 8 is a top view thereof.

The broken line showing of the LED display casing is for the purpose of illustrating portions of the LED display casing and forms no part of the claimed design.

1 Claim, 8 Drawing Sheets
